UNITED STATES PATENT OFFICE.

FREDERICK LAIST AND JAMES ORR ELTON, OF ANACONDA, MONTANA, ASSIGNORS TO ANACONDA COPPER MINING COMPANY, OF ANACONDA, MONTANA, A CORPORATION OF MONTANA.

ELECTRODEPOSITION OF METALS.

1,255,437.

Specification of Letters Patent.

Patented Feb. 5, 1918.

Application filed June 16, 1916. Serial No. 104,085.

To all whom it may concern:

Be it known that we, FREDERICK LAIST and JAMES ORR ELTON, citizens of the United States, residing at Anaconda, in the county 5 of Deerlodge and State of Montana, have invented certain new and useful Improvements in the Electrodeposition of Metals, of which the following is a specification.

This invention relates to the recovery of 10 metals, specifically zinc, from such aqueous solutions of their salts as have undergone a process of purification to adapt them for use as electrolytes. The object of the invention is to provide a simple means for determin- 15 ing the efficiency of the purification and the suitability of the solution for electrodeposition of the metal.

In the case of zinc salts for example it is well known that the efficiency of the electrodeposition of the metal, as well as the quality 20 of the deposit, is dependent upon the purity of the electrolyte. In the particular case of zinc it has been observed that the ill-effects of an impure solution accidentally introduced into the electrolytic system are noticeable for several days after the purity of the inflowing solution has been restored.

According to the present invention we equip a test cell or indicator cell with electrodes similar to those employed in the main electrodepositing system; and we so place this indicator cell as to receive in continuous flow a small proportion of the purified solution flowing to the storage tanks from which 35 the main electrolytic cells receive their supply. The current and other conditions in this indicator cell being maintained as in the main cells, the quality of the deposit therein, and the current efficiency of the deposition, 40 serve as an accurate indication of the purity of the electrolyte; and in case any portion of the solution falls below the fixed standard of purity, such portion can be returned to the purification system before passing into 45 the electrolytic cells. For example, by providing a number of tanks in the storage system, and closely observing the operation of the indicator cell, the return for further purification of the contents of a single tank

will usually suffice to avoid a prolonged disturbance of the entire electrolytic system, with its attendant trouble and expense.

While the system as above described is particularly advantageous as applied to the electrodeposition of zinc by reason of the marked effect of minute quantities of certain impurities upon the deposition of this metal, it will be understood that the invention may be applied in other electrolytic systems where the indications afforded by a test cell would be of value in controlling the operation.

The accompanying drawing is a diagram or flow-sheet representing a system arranged in accordance with this invention. In this flow-sheet, A represents the indicator or test cell, receiving a constant flow of purified liquor and returning its acid effluent to the leaching system: and B, B' are the main storage tanks for the purified solution. Preferably each storage unit is capable of holding at least 24 hours' supply of purified electrolyte for the main cells, and the contents of either unit may be returned in case of need, and in accordance with the indications of the test cell A, to the purifying system, before any portion thereof has passed to the main electrolytic cells. The number of such storage units may of course be increased as desired.

80

We claim:

1. In the deposition of metals by electrolysis, the combination with a purifying system, a storage system, and a main electrolytic system, of an indicator cell in the line of flow of the solution between the purifying and storage systems.

2. In the deposition of zinc, the combination with a purifying system, a storage system, and a main electrolytic system, of an indicator cell in the line of flow of the solution between the purifying and storage systems.

In testimony whereof, we affix our signatures.

FREDERICK LAIST.
JAMES ORR ELTON.
